MACHINE FOR APPLYING BELT LACERS
AND THE LIKE

James K. Diamond, Grand Rapids, Mich.

Application January 27, 1939, Serial No. 253,055

10 Claims. (Cl. 1—49.4)

This invention relates to improvements in machines for applying belt lacers and the like.

The main objects of this invention are:

First, to provide a belt lacing machine or machine for applying belt lacers which may be used as a portable unit and one which is very powerful and at the same time comparatively light in weight.

Second, to provide a machine of the class described which has a wide range of adjustment and may be quickly adjusted to belts for the setting of fasteners or belt hooks on lacings in belts of different thicknesses.

Third, to provide a machine of this character in which the belt lacings are very effectively set and in a manner not to cause distortion thereof.

Objects relating to details and economies of the invention will appear from the description to follow. The invention is defined and pointed out in the claims.

A preferred embodiment of the invention is illustrated in the accompanying drawings, in which:

Fig. 1 is a front elevation of a belt lacing machine embodying the features of my invention with the jaw members thereof in open position.

Fig. 2 is an end elevation looking from the left of Fig. 1 showing a machine as mounted upon a bench or work table.

Fig. 3 is a fragmentary view mainly in longitudinal section on line 3—3 of Figs. 2 and 4 with the jaw members in closed or actuated position.

Fig. 4 is a fragmentary plan view with the jaw members in open position.

Fig. 5 is a fragmentary front view with a set of belt lacing hooks in position in the jaw unit and a fragment of a belt in position to receive the fasteners.

Fig. 6 is a fragmentary view in section on line 6—6 of Figs. 1 and 3 showing certain of the structural details.

In the embodiment of my invention illustrated, the frame comprises a pair of side members 1, connected in spaced relation by suitable cross members 2. These side members are, as shown, stamped up from suitable gauge plates and have flanges 3 at the lower edges thereof which constitute feet or they may be used as attaching flanges to receive bolts 4 for securing the machine to a bench or table 5. However, the unit is especially well adapted as a portable unit—that is, it may be carried about a factory for convenient use.

I provide a pair of lever-like jaw members

which in this embodiment are formed of a plurality of plates 7 arranged in spaced relation, as illustrated in Fig. 4. These plates are rigidly connected together so that in effect they form a jaw unit. At their lower ends, they are connected by cross bars or rods 8 which have reduced portions 9 engaging the horizontal slots 10 in the side plates 1, thereby supporting the lower ends of the jaw members for limited sliding movement on the frame.

The jaw members are provided with fulcrumming rockers 11 having vertically curved outwardly facing faces 12 coacting with the abutment members 13. These abutment members comprise the abutment blocks 14 and connecting cross member 15. The abutment members are carried by the rods 16 which are rotatably arranged in and extend through bracket-like supports 17 mounted on the side members 1 of the frame, these members being carried by the pins 18 projecting inwardly from the side members 1 and having spacing sleeves 19 thereon—see Figs. 3 and 6. There are a pair of these bracket-like supports 17, one for each rod 16, and they are secured to the opposite side members 2, as illustrated in Fig. 6, hence it is not deemed necessary to further illustrate this duplicate construction.

The rods 16 are threaded at one end, as at 20, to receive the nuts 21 which have notched flanges 22 adapted to receive pins 23 for retaining the nuts in their adjusted positions. The nuts constitute thrust members for the abutments. On the opposite ends, the rods are provided with sprocket wheels 24, the hubs 25 of which are secured to the rods and serve as thrust members for the abutments at that end of the rods.

The rods 16 extend parallel to the plates 7 of the jaw members 6 lying in the vertical space between the respective pairs of said plates.

The sprockets are connected by the sprocket chain 26 and one of the sprockets is provided with a crank 27 which provides means for simultaneously adjusting the abutments to and from each other, this adjustment being made to accommodate belts of different thickness.

The jaw members are urged against their abutments by means of springs 28 arranged on the rods with their inner ends in supporting engagement with the sleeves 29 on the rods and their outer ends engaging thrust members 30 which are engaged with the jaw member plates at 31. These thrust members 30 have apertures receiving the rods 16 of sufficient size to accommodate any slight vertical movement of the thrust mem-

bers relative to the rods occurring upon rocking of the jaw members. However, the movement of the thrust members 30 with reference to rods 16 is practically exclusively parallel thereto and 5 coaxial therewith.

The jaw members are provided with opposed jaw thrust bars or members 32 which extend across the plates and are secured to their inner edges in a plane above the fulcrum points of 10 the jaw members so that when the jaw members are actuated or rocked on their fulcrums in one direction, the jaw thrust bars are moved toward each other and in the opposite direction they are moved away from each other. In the structure illustrated, the jaw thrust bars 32 are secured to the plates by means of screws 33 which are arranged through cross pieces 34 extending between pairs of plates—see Figs. 3 and 4. This 15 permits removal or changing of the thrust bars 20 as occasion may require.

In the embodiment illustrated, I provide a very powerful actuating means consisting of a pair of toggle links 35 which are pivotally mounted on the cross bars 8 at their outer ends and 25 are pivotally connected to each other by the pivot member 36 which is provided with vertical guideways at each end at 37, see Fig. 6. The rack 38 is connected to the member 36 and is provided with a driving pinion 39, it being supported in driving engagement by this pinion by 30 the roller 40. The pinion is provided with a shaft 41 projecting through the front frame member and having a double crank 42 thereon. This toggle and rack and pinion actuating means 35 taken in connection with the mounting and fulcrumming of the jaw members provides a very powerful actuating means and at the same time one in which there is no excessive or severe strains on any of the parts.

40 The fastener setting unit illustrated is substantially that of my Patent No. 1,984,634 dated Dec. 18, 1934, and it comprises a fastener holder 43 having a series of transverse slots 44 therein designed to receive and hold in properly spaced 45 relation the lacing fasteners 45. This holder has a longitudinal hole 46 therein adapted to receive the retaining pin 47 which extends above the bights of the hooks or fasteners, as shown in Fig. 5.

50 The jaw unit comprises a pair of opposed jaws 48. The jaw unit is provided with end plates 49 which have cammed slots 50 and 51 engaged by the pins 52 and 53 respectively as is described in detail in my said patent.

55 The jaw unit is mounted on the jaw thrust bars 32, the jaw unit having bars 54 secured across the tops thereof and terminating in arms 55 having slots 56 engaging pins 57 on the ends of the jaw thrust members 32. This allows a semi-floating movement of the jaw unit as the jaws are 60 swung to closed position by the actuation of the jaw members. It will be noted that the cross pieces 54 overhang the upper edges of the jaw thrust members.

65 With a set of belt lacing hooks or fasteners in position a belt, as 58, is positioned between them as shown in Fig. 5, the jaw members actuated to close them thereby forcing the prongs of the fasteners into the belt as shown in Fig. 3. In 70 the closed position, it will be noted that the jaw thrust bars or members 32 are in parallel relation to the outer sides of the jaws 48—that is, they are in flat clamping engagement therewith 75 and the faces of the jaws 48 are in parallel rela-

tion to each other when the fasteners are completely set as shown in Fig. 3.

The machine may be quickly adjusted to belts of different thicknesses by adjusting the abutment members. Inasmuch as the jaw members 5 have rocking fulcrumming engagement with these abutment members, there is little if any frictional engagement and actuating means such as the toggle can perform efficiently in actuating the members to close the jaw thrust members. 10 It will be observed that in addition to the toggle action, there is a very effective leverage and this of course may be varied considerably but the structure I have shown is sufficiently powerful 15 for a wide range of belts and the parts are such that they can be economically produced and assembled.

I have illustrated and described a very satisfactory embodiment of my invention. I have not attempted to illustrate or describe other embodiments or adaptations which I contemplate 20 as it is believed that this disclosure will enable those skilled in the art to embody or adapt my improvements as may be desired.

Having thus described my invention, what I 25 claim as new and desire to secure by Letters Patent is:

1. In a structure of the class described, the combination with a frame comprising spaced side members having horizontally disposed slots therein, of jaw members comprising a plurality of spaced vertically disposed plates, cross bars connecting the lower ends of said plates and slidably supported in said slots, fulcrum rockers having vertically curved faces mounted on the outer edges of said plates, opposed jaw thrust bars mounted on the inner edges of said plates in a plane above the said fulcrum rockers, opposed abutment members for said fulcrum rockers, means for simultaneously actuating said jaw members, a spring connecting said cross bars and acting to open said jaw members, and a jaw unit comprising a pair of jaws carried by said jaw thrust bars, said thrust bars being adapted when the jaw members are actuated to clampingly 45 engage the sides of the jaws.

2. In a structure of the class described, the combination with a frame comprising spaced side members having horizontally disposed slots therein, of jaw members, cross bars connected to said jaw members and slidably supported in said slots, fulcrum rockers having vertically curved faces mounted on the outer edges of said plates, opposed jaw thrust bars mounted on the inner edges of said jaw members in a plane 55 above the said fulcrum rockers, opposed abutment members for said fulcrum rockers, a jaw unit comprising a pair of jaws carried by said jaw thrust bars and adapted when the jaw members are actuated to clampingly engage the sides 60 of the jaws, and means for simultaneously actuating said cross bars to approach and retract said jaw members.

3. In a structure of the class described, the combination of jaw members mounted at their 65 lower ends for limited sliding movement, fulcrum rockers on said jaw members having outwardly facing curved faces, opposed jaw thrust members disposed in a plane above said fulcrum rockers, opposed abutment members for said fulcrum rockers, a jaw unit comprising a pair of jaws carried by said jaw thrust members, and means to actuate said jaw members to rock said rockers on their respective abutment members, said thrust members being adapted when the jaw 75

members are actuated to clampingly engage the jaws.

4. In a structure of the class described, the combination of jaw members mounted at their lower ends for sliding movement and provided with fulcrum rockers having outwardly facing curved faces, opposed abutment members coacting with said fulcrum rockers, means for simultaneously adjusting said abutment members to and from each other, opposed jaw thrust members disposed so that they are moved to and from each other by the fulcruming movement of said jaw members, a toggle actuating means connecting the lower ends of said jaw members, a spring acting to move the lower ends of said jaw members toward each other to thereby open the jaw members, and a belt lacing setting unit supported by said jaw members and actuated to closed position by the actuation of said jaw members, the jaws of said lacing unit being connected to said jaw members so that they are automatically opened by the opening of said jaw members.

5. In a structure of the class described, the combination of jaw members, means for confining a portion of said jaw members to lateral sliding movement, opposed abutment members on which said jaw members are fulcrumed, means for simultaneously adjusting said abutment members to and from each other, opposed jaw thrust members disposed so that they are moved to and from each other by the fulcruming movement of said jaw members, means for simultaneously actuating said jaw members, and a belt lacing setting unit supported by said jaw members and actuated to closed position by the opening of said jaw members.

6. In a structure of the class described, the combination of opposed abutment members mounted for adjustment to and from each other, jaw members slidably supported at their lower ends and having fulcruming rockers coacting with said abutment members, and jaws carried by said jaw members and so disposed relative to the fulcruming of said jaw members that the jaw members when closed have a lever-like jaw closing action, and a toggle for actuating said jaw members comprising links pivotally connected to the said jaw members and to each other, a rack connected to the links, and a driving pinion operatively associated with the rack.

7. In a structure of the class described, the combination of opposed abutment members mounted for adjustment to and from each other, jaw members having fulcruming members coacting with said abutment members, and jaws pivotally mounted on said jaw members and so disposed relative to the fulcruming of said jaw members that the jaw members when closed have a lever-like jaw closing action, and means for simultaneously actuating said jaw members.

8. In a structure of the class described, the combination of jaw members supported at their lower ends for limited sliding movement, opposed abutments with which said jaw members have fulcruming engagement, means for simultaneously adjusting said abutments, jaw thrust members disposed on said jaw members so that they are moved toward and from each other by the fulcruming movement of said jaw members, and a belt lacing setting unit comprising a lacing holder and a pair of opposed lacing setting jaws operatively associated therewith, and arms on said jaws having slotted engagement with said jaw thrust members, said jaw thrust members being adapted when the jaw members are in actuated position to parallel and clampingly engage the said lacing setting jaws.

9. In a structure of the class described, the combination of jaw members supported at their lower ends for limited sliding movement, opposed abutments with which said jaw members have fulcruming engagement, jaw thrust members disposed on said jaw members so that they are moved toward and from each other by the fulcruming movement of said jaw members, and a belt lacing setting unit comprising a lacing holder and a pair of opposed lacing setting jaws operatively associated therewith, and arms on said jaws having slotted engagement with said jaw thrust members, said jaw thrust members being adapted when the jaw members are in actuated position to parallel and clampingly engage the said lacing setting jaws.

10. In a structure of the class described, the combination of jaw members mounted for fulcruming movement and having a portion thereof restrained for lateral sliding movement, means for simultaneously actuating said jaw members on their fulcrums, the fulcrums being simultaneously adjustable to and from each other, and a lacing setting unit comprising a pair of jaws pivotally mounted on said jaw members.

JAMES K. DIAMOND.
